United States Patent Office

Des. 189,069
Patented Oct. 18, 1960

189,069

MOTION PICTURE CAMERA

Frederick Hertzler, St. Clair Shores, and Raymond A. Grosso and Dominic Saporito, Royal Oak, Mich., assignors to Sylvania Electric Products Inc., a corporation of Delaware

Filed Sept. 3, 1959, Ser. No. 57,424

Term of patent 14 years

(Cl. D61—1)

FIG. 1

FIG. 2

FIG. 3

FIG. 4

Figure 1 is a perspective view of a motion picture camera showing our new design;

Figure 2 is a bottom plan view;

Figure 3 is a left hand side elevation; and

Figure 4 is a rear view.

We claim:

The ornamental design for a motion picture camera, substantially as shown.
